UNITED STATES PATENT OFFICE.

KENNER TAYLOR, OF FRANKFORT, KENTUCKY, ASSIGNOR OF ONE-HALF
TO JOHN MEAGHER, OF SAME PLACE.

WHISKY-TESTER.

SPECIFICATION forming part of Letters Patent No. 413,154, dated October 15, 1889.

Application filed July 31, 1889. Serial No. 319,334. (No model.)

To all whom it may concern:

Be it known that I, KENNER TAYLOR, a citizen of the United States, residing at Frankfort, in the county of Franklin and State of Kentucky, have invented certain new and useful Improvements in Whisky-Testers; and I do hereby declare the following to be a full, clear, and exact description of the invention, such as will enable others skilled in the art 5 to which it appertains to make and use the same.

This invention relates to that class of devices whereby whisky, singlings, and other spirits are tested as to proof.

15 In all distilleries there are tubs used for the reception of the spirits made, and the tops of the tubs are tightly covered and provided each with a man-hole, the door to which is locked, and the key is carried by a government store-keeper. Whenever the distiller or his representative wants to try the contents of said tubs as to its proof he has to send for the store-keeper to unlock the tub, and after 20 the test is made the tub is again locked. This 25 may occur twenty or thirty times daily, and frequently it happens that at the moment when a test should be made the store-keeper is elsewhere occupied, and consequently the whisky runs too low in proof before he can 30 be gotten, and to correct this the high wines of the next doubling have to be broken into, thus entailing a considerable loss. From the same cause the whisky is frequently pumped over at too high a proof, the whisky-runner 35 having guessed at the proof rather than to take the time and trouble to call the store-keeper. Then water must be carried to the cistern-room, where the whisky is drawn off, to reduce its proof, again entailing loss of whisky, 40 labor, and time. These difficulties and many others with which the practical distiller is familiar in the present method of testing whisky, singlings, and other spirits, I propose to obviate by providing means whereby the 45 tests may be made as frequently as may be desired without opening the tub containing the same, and without exposing any portion of the spirits to be wasted or stolen or in any way touched, the standard instruments now 50 in use by the government being employed.

To this end my invention consists, first, in a test-chamber secured upon and opening into the tub, and having one or more transparent sides through which the result of the test may be observed; second, in certain minor details whereby a sample of the spirits may be drawn up from the tub into the chamber, and whereby the usual standard testing device employed by the government—a hydrometer—may be immersed freely in the sample, 55 and whereby the sample may be discharged into the tub after the test is made, and, third, in a thermometer-cover of peculiar form, as hereinafter described and claimed, reference being had to the accompanying drawings, in 60 which—

Figure I represents a vertical section of my invention and a portion of a tub to which it is attached. Fig. II is a horizontal sectional view looking down upon line x. Fig. III is a 70 horizontal section of the thermometer-cover on a larger scale than the same is shown in Figs. I and II.

10 represents the portion of a top of a tub containing the spirits. 75

13 represents my testing-chamber. It consists of a glass tube 14, a base-plate 11, a top ring 15, a cap 16, and side rods 17. The glass tube is transparent and open at both ends. It is tightly cemented to the base-plate 11 80 and to the ring 15. The base-plate 11 is annular and is rigidly secured to the tub over and around a hole therein by means of bolts 12, whose screw-nuts may be on the inside of the tub to prevent the whole device being removed or the interior tampered with. The cap 16 is hinged to the top ring at 18, so that it may be opened, and it may be locked by means of the staple 19 and a government lock. The rods 17 connect the ring 15 with 90 the base-plate 11, and form therewith a rigid frame for the glass tube 14. 85

21 is a crib for freely supporting the hydrometer. It consists of the staves 22, secured at the top to an annular plate 23, and 95 provided with hoops 24 and with a concave perforated bottom 25. This should be in some manner cushioned with elastic material—as, for instance, by means of a rubber or cork floor 26—to prevent breaking the glass hy- 100

drometer in rapid handling. The plate 23 is fitted to rest upon the ring 15, and the crib may be freely lifted out of the test-chamber when the cap 16 is open for cleaning or other purposes.

27 is the thermometer-cup, consisting of a thin brass tube 28, open at both ends, but screwed at its lower end into a bottom 29, with which it may be made tight in any usual way, such as by means of the packing-ring 30. One side of the cup is provided with a thermometer 31, as usual; but instead of the usual flat glass covering for the thermometer, I provide a convex glass 32, having the curve 15 of a cylindrical segment, with its edges secured to the cup beyond the edges of the thermometer. By this means the thermometer receives more light, and it may also be seen from any direction as clearly as though 20 not covered, thus having great advantage over a flat glass in permitting the scale of the thermometer to be read.

33 is a puppet-valve seated in the bottom 29 and provided with a depending stem 34, to be engaged by a lever 35, which is pivoted to a portion of the bottom 29.

36 is a trip-rod passing up through the base-plate 11, and provided with a spring 37, to hold it normally raised, and having a knob 38. The lever 35 is weighted at 39 to keep the end beneath the valve down.

40 represents two guide-rods of the length required to reach the bottom of the tub. They are fitted to slide in guide-tubes 41, which I 35 prefer to form by grooving the rods 17, which are fixed through the base-plate 11, and the guide-rods 40 are fixed rigidly at their lower ends to the bottom piece 29 and connected at their upper ends by a stiff ring 42.

43 represents a handle attached to the ring or to one of the rods.

44 represents a barrel-wheel journaled in a portion of the base-plate 11 and circumferentially toothed to engage a rack 46 on one 45 of the rods 40, and 45 is a spring within the barrel and acting thereon to revolve it in the direction to lift or balance the weight of the cup 27, whether the same be full or empty, including also the weight of the bottom 29, 50 rods 40, and other attachments.

To operate this invention, the cup 27 may be let down to the desired depth by means of the handle 43 and connections described, and allowed to fill. If the liquor is low down in 55 the tub, the weight 39 will be pressed upon the bottom of the tub and will raise the valve 33, thus permitting liquor to enter the cup at the lower end, and the valve will close as soon as the cup is raised. By quickly-repeated thrusts the cup will be filled with liquor. Then it may be drawn up into the test-chamber 13. In doing that the crib 21 will be immersed in the cup and the hydrometer carried in the crib will be permitted to float 60 in the liquor. Now both the hydrometer and thermometer scales may be observed and read through the glass of the chamber, and yet

not a drop of the liquor can be withdrawn from the tub, nor has the tub been in any way opened to permit loss by evaporation or otherwise. The spring 45 and intermediate gearing will hold the cup raised until it is pushed down by force, and the liquor may be returned to the tub through the valve 33 by pressing on the knob 38, which, acting through 75 the lever 35, will open the valve.

The minor details of this device may be variously changed to produce practically the same result without affecting the principle of my invention—as, for example, the two rods 80 40, supporting the cup 27, may be differently located and a different balancing device from the spring 45 and the gearing shown may be used; or the balance may be dispensed with. A chamber made transparent at one side 85 might answer the purpose to a limited extent; but I prefer the glass tube transparent at all sides, as described. The chamber might also be adapted for limited use by being attached to one side of the tub near its top; 90 but this would involve a different method of bringing the test-cup around the crib, and it would lessen the storage capacity of the tub, or else be useless when the liquor filled the tub.

Having thus fully described my invention, what I believe to be new, and desire to secure by Letters Patent, is the following:

1. The combination of a covered liquor-tub, a chamber thereon having one or more transparent sides, a crib for loosely supporting a hydrometer hung within the chamber, a thermometer-cup adapted to rise within the chamber and around the crib, there being an opening from the chamber into the tub through 105 which the said cup may pass, and a rod or rods attached to the cup, whereby it may be dipped in the tub and brought into the said chamber, substantially as shown and described.

2. The combination of a tub having a hole in its top, a transparent cover for the hole, a crib or equivalent hydrometer-holder beneath the said cover, and a cup adapted to be raised around the said crib, substantially as shown 115 and described.

3. The combination of a tub having a hole in its top, transparent cover for the hole, a cup adapted to be raised through the hole beneath the cover, a thermometer secured to one 120 side of the cup, and a transparent cover to the thermometer, convex on its outer face, substantially as shown and described.

4. The combination of a covered liquor-tub having a hole in the cover, a transparent 125 chamber secured over the said hole, a crib for holding a hydrometer removably suspended within the chamber, and a cover hinged to the chamber and adapted to be locked, substantially as shown and described.

5. The combination of a liquor-tub having a hole in its top, a transparent chamber secured over the hole, a thermometer-cup adapted to pass up through the hole, a guide-

rods attached to the cup, whereby it may be sunk into and drawn up out of the contents of the tub, and guides for the said rods fixed relatively to the said chamber, whereby the 5 raising of the rods will draw and direct the cup into the chamber.

6. The combination of a thermometer-cup, guide-rods therefor, one of which is provided with a toothed rack, a support provided with 10 guides through which the rods may slide, a toothed barrel-wheel journaled on the said support to engage the said rack, and a balance-spring within the barrel, substantially as shown and described.

15 7. The combination of a thermometer-cup,

a puppet-valve in its bottom having a depending stem, a lever hung to the bottom of the cup and provided with a weight beneath the said stem, rods supporting the cup, fixed guideways for the rods, a trip-rod located in 20 the guide-frame over the free end of the said lever, and a spring for supporting the said trip-rod, substantially as shown and described.

In testimony whereof I affix my signature in 25 presence of two witnesses.

KENNER TAYLOR.
